UNITED STATES PATENT OFFICE

132,810

DESIGN FOR A BOTTLE CLOSURE

Harry C. Glessner, Findlay, Ohio, assignor to The Glessner Company, Findlay, Ohio, a corporation of Ohio

Application October 8, 1941, Serial No. 103,683

Term of patent 3½ years

To all whom it may concern:

Be it known that I, Harry C. Glessner, a citizen of the United States, residing in Findlay, county of Hancock, and State of Ohio, have invented a new, original, and ornamental design for a Bottle Closure, of which the following is a specification, reference being had to the accompanying drawing, forming a part thereof.

In the drawing:

Fig. 1 is a top plan view of a bottle closure, showing my new design; and

Fig. 2 a side perspective view thereof.

I claim:

The ornamental design for a bottle closure, as shown.

HARRY C. GLESSNER.
